UNITED STATES PATENT OFFICE

PETER TARARO, OF CHICAGO, ILLINOIS

DESIGN FOR AN INKWELL STAND

Application filed March 1, 1928. Serial No. 25,635. Term of patent $3\frac{1}{2}$ years.

To all whom it may concern:

Be it known that I, PETER TARARO, a subject of the King of Italy, residing at Chicago, in the county of Cook and State of Illinois, have invented a new, original, and ornamental Design for Inkwell Stand, of which the following is a specification, reference being had to the accompanying drawing, forming a part thereof.

The figure is a view in perspective of an inkwell stand embodying my new design.

I claim:

The ornamental design for an inkwell stand as shown.

In witness whereof, I hereunto subscribe my name, this 25th day of February, 1928.

PETER ^{his} X TARARO.
